UNITED STATES PATENT OFFICE

HAROLD V. STUART, OF MILWAUKEE, WISCONSIN

SHOULDER STRAP MAINTENANCE DEVICE

Application filed November 18, 1932. Serial No. 643,261.

This invention relates to an improved accessory or device primarily adapted for feminine use, and particularly constructed as a retainer or holder for a group of shoulder straps such as are provided on present-day undergarments and lingerie.

I am aware of the fact that many different kinds of retaining clips and similar holders have been devised for this purpose. In order to devise a comparatively refined and improved structure, I have discovered an ideal and simplified arrangement of structural features carefully selected and organized to provide a single unit which will not only hold the shoulder straps in group relationship but will securely anchor the straps to the outergarment or dress as the case may be.

In carrying the principles of this invention into actual practice, I have evolved and produced an appreciable contribution to the trade and the art which is ideal for the purpose, excellent in nature, and unusually handy in accomplishing the desired results.

Other features and advantages of the invention will become more readily apparent from the following description and drawing.

In the drawing:

Figure 1 is a longitudinal section through a fragmentary portion of the dress or outer garment showing the manner in which the improved device shown in elevation, is effectively secured in place.

Figure 2 is an enlarged elevational view 35 with portions broken away to disclose otherwise concealed details.

Figure 3 is a bottom plan view of the device.

To begin with, I call attention first to one 40 of the fundamental details of the assembly which is here shown in the form of a bendable or pliable carrier strip 4. This is of general rectangular form and of appropriate longitudinal and transverse dimensions and in 45 practice is made from "celluloid" rubber or any equivalent marketed material. "Celluloid" has been found to be ideal for the purpose in that it possesses the requisite resilient properties and may be colored in different 50 shades to correspond to the particular color

of the dress to which the device is designed for attachment.

At its opposite ends the strip is formed with slots 5 and 6. On its underside and at one end the celluloid strip is provided with a 55 headed stud 7 forming one of the elements of a quick separable fastener, this being located adjacent the slot 6.

I next call attention to a shoulder strap retaining ribbon 8 which is of a color to 60 correspond with the strip 4 and which is secured at one end by a suitable clip 9 to the intermediate portion of the top face of the carrier strip 4. Then, the free end portion 10 is drawn through the slot 5 as indicated 65 at 11 and terminates in a hem 12 which is secured to a slot 13 formed in a suitably shaped celluloid tab 14. This tab carries the socket member 15 of the fastener which is designed for separable connection with the stud 7.

The portion 10 of the ribbon, together with the backing strip 4 defines a loop-like hanger through which the shoulder straps (not shown) are passed in the usual way.

I next call attention to the attaching ribbon 16 which is of a length greater than the strip 4 and which has its end portions threaded downwardly through slots 5 and 6 and extended beyond said slots to permit the terminal ends 17 and 18 to be permanently stitched 75 to the seam of the dress or outergarment 19 as seen in Figure 1. This ribbon 16 is slideable with respect to the strip so as to permit the requisite adjustment to be made for expeditious sewing.

Moreover, by bringing the end portions 17 and 18 through the slots 5 and 6 in the manner shown, they cover the major portions of the opposite ends of the strip 4 to 80 serve as protectors and to prevent said ends 85 from annoying the wearer.

The gist of the invention is in the provision of an elongated flexible backing strip or carrier having slotted ends with a maintenance ribbon secured thereto and threaded through one of the slots, separable means for fastening the free end of said ribbon to a corresponding end of the strip, and an attaching ribbon 16 also having its ends 90 threaded through the slots 5 and 6 to be con- 95 nected with the carrier strip 4. 100

veniently stitched to the dress. While I have used the term "ribbon" it is understood that these elements may be more broadly referred to as "straps" for the purpose of construing the claims.

As this device will be found very practical to be made and adapted in house dresses, aprons, or garments of washable material, the vital point in using such compositions is that the entire accessory may be left sewed in these housedresses or aprons while washed or ironed, and will not effect its construction or removal from dress or apron.

The ribbon may be made of various grades, rib, smooth, or of a material to be adapted to give best results when undergoing a washing or ironing. The main object of this invention is to be specifically recognized as a permanent dress or garment accessory.

It is thought from the foregoing description that the advantages and novel features of the invention will be readily apparent. It is to be understood that changes may be made in the construction and in the combination and arrangement of the several parts provided that such changes fall within the scope of the appended claims.

I claim:

30 1. As a new article of manufacture, a shoulder strap retaining device comprising a resilient carrier strip, an attaching ribbon connected thereto, said ribbon having its opposite ends arranged to permit sewing of said ends to the dress, a retaining ribbon secured to said strip at one end, and separable fastening means on the free end of said second ribbon and corresponding end of said strip.

40 2. A multiple strap holder of the class described comprising an elongated strip of pliable material formed at one end with a transverse slot, a strap retaining ribbon secured at one end to the intermediate portion of said strip, having its intermediate portion passed through said slot, a tab secured to the free end of said ribbon, a socket fastener member carried by said tab, a headed retaining stud carried by one end portion of said strip for co-operation with said socket member, and means for attaching said strip to the dress.

50 3. As a new article of manufacture, a shoulder strap maintenance device comprising an elongated strip of pliable material formed at opposite ends with transverse slots, a retaining ribbon secured at one end by a clip to the intermediate upper side of said strip and having its intermediate portion passed through one of said slots, a tab secured to the extremity of said ribbon, a fastener element carried by said tab, a co-operable fastener element carried by the adjacent end of the strip, and an attaching ribbon of a length greater than said strip having its opposite

end portions threaded through said slots and extending beyond the slotted ends for attachment to the dress.

In testimony whereof I affix my signature.

HAROLD V. STUART.
